UNITED STATES PATENT OFFICE.

WILLIAM HENRY HAWKES, OF NYACK, NEW YORK.

SADIRON-HOLDER.

1,332,039.

Specification of Letters Patent.

Patented Feb. 24, 1920.

Application filed December 6, 1917. Serial No. 205,830.

To all whom it may concern:

Be it known that I, WILLIAM H. HAWKES, a citizen of the United States, residing at Nyack, in the county of Rockland, State of New York, have made a certain new and useful Invention in Sadiron-Holders, of which the following is a specification.

This invention relates to sad iron holders, and particularly to cushioned non-conducting holders for hand operated irons of the common household and laundry type.

The object of the invention is to provide a sad iron holder which is simple in structure, efficient in operation, and economical to manufacture.

A further object of the invention is to provide a holder of the character described which will positively engage the handle of the iron and which will prevent slipping between the holder and the iron handle.

A further object of the invention is to provide a holder of the character described which will allow the use of a heated iron without the necessity of cooling the handle thereof.

Further objects of the invention will appear more fully hereinafter.

The invention consists substantially in the construction, combination, location, and relative arrangement of parts, all as will be more fully hereinafter set forth as shown by the accompanying drawing, and finally pointed out in the appended claims.

Referring to the drawings:

Figure 1 is a top plan view of an iron holder embodying my invention.

Fig. 2 is a bottom view of the same.

Fig. 3 is a view in side elevation of the same, parts broken away and parts in section.

Fig. 4 is a sectional view taken on the line 4, 4, Fig. 3, looking in the direction of the arrows.

Fig. 5 is an enlarged detail sectional view similar to that shown in Fig. 4, and more clearly illustrating the means employed for engaging the handle of the iron.

Fig. 6 is a sectional view taken on the line 6, 6, Fig. 3, looking in the direction of the arrows.

The same part is designated by the same reference character wherever it occurs throughout the several views.

My present invention relates more specifically to a holder for irons containing certain marked advantages and improvements

over a holder of this class shown and described in my co-pending application, Serial No. 111,188, filed July 25, 1916, which advantages will be more fully hereinafter pointed out and discussed.

Referring to the drawing: I show at 1 the usual smoothing iron or sad iron provided with the handle 2 in the usual manner. The holder forming the subject matter of my invention is comprised of a plurality of layers or leaves of heat insulating material, the bottom layer being preferably of woven textile material, and the top layer being of a relatively softer material as will be more fully hereinafter described. Interposed between these two layers are a plurality of layers of paper and card-board, or other suitable heat insulating material, suitably hinged to each other to allow a free bending movement of the holder to engage and release the handle of the iron without breaking or cracking the layers of heat insulating material. Permanently attached upon one of the outer sides of the body of the holder is a pocket 3 adapted to receive all of the fingers of the operator's hand, and having an outer side wall comprised of a textile fabric 4, and preferably reinforced by a thin metal plate 5 extending longitudinally of the holder and nearly to the top of the pocket. While I prefer this form of construction for its strength and durability I wish it to be understood that I am not to be limited or restricted to any specific details concerning the pocket thus described. On the opposite side of the body portion is another pocket of smaller size indicated at 6 to receive the thumb of the operator, thus providing means whereby an adequate grip is obtained of the holder and through the medium thereof of the iron itself. On the under surface of the holder I provide three metal strips indicated at 7, 8, and 9. The three strips substantially cover the oval under surface of the holder, the strips 7 and 9 being the outer strips and the strip 8 being the center strip extending throughout the longitudinal length of the holder and its approximate center. The inner ends of the strips 7 and 9 are flanged as indicated at 10 so that the same extend over and overlap the central strip 8 as will be readily seen. Secured to the body of the strips 7 and 9 adjacent the flanged portions 10 thereof are what I term flange holders 11 and 12 respectively, one edge thereof being flanged

inwardly to closely adhere to the contour of the flange 10 of the strips 7 and 9. The strips 7 and 9 may be secured in any suitable way to the bottom surface of the holder, and 5 I have shown for this purpose rivets 13 to which however I am not to be limited as any suitable means may be employed. Likewise members 11 and 12 can be secured in any suitable manner to the plates 7 and 9, 10 and while I have shown rivets 14 for this purpose it is to be understood I am not to be limited in this respect. The outer edges of the members 11 and 12 are indented and upwardly flanged as indicated at 15. These 15 flanges, when the holder is positioned over the handle 2 of the iron 1, clinch over and secure the body of the handle 2. This type of engagement between the holder and handle I have found in practice to be efficient and a marked advantage over other engaging means heretofore employed for this purpose. The front end of the holder, and referring to the metal strips 7 and 9, are bent downwardly as indicated by members 20 10, as are likewise the end portions 16 of the strips 11 and 12. Likewise the end portion 17 of the center strip 8 is bent downwardly so that the end portions of the members 11, 12, 7, 9, and 8, when the holder is closed over the handle 2 of the iron 1, effectively form a 25 pocket to engage the forward end of the handle, thus preventing slipping between the handle and the holder, as will be readily understood. To effect the clenching of 30 the holder when in use I provide comparatively large rivets 17 at the head or forward end of the members 11 and 12 which effectively clinch when the holder is in use under the handle 2 and securely 35 lock the same in place. Thus it will be seen that this arrangement of gripping between the cover and the shank of the handle 2 at the curve thereof affords a leverage so that the operator can use the toe or 40 heel of the iron and get a smoother surface with the same with less pressing on his part, or in other words, with the use of less strength. Likewise the curved ends and 45 rivets 17 of the respective metal strips at the forward end which forms a pocket to receive 50 the curved end of the iron handle enables the operator to get nearer to his work with the point of his iron while preventing slipping of the holder relative to the handle of 55 the iron, thus enabling the operator to freely use the point of the iron as it is customary to do on starched bosoms or cuffs and around buttons and creases. As above described the 60 cardboard members or other heat insulating members interposed between the inner and outer surfaces of the holder are hinged in an overlapped condition as indicated at 20 which allows the opening and closing of the holder without breaking the heat insulated

material employed. This arrangement of 65 hinging the cardboard strips allows the use of cardboard which is the best heat insulating material for this work and is cheap where otherwise the same could not be employed. There is another feature with the 70 present type of holder which is not incorporated in any other holder of which I am aware, namely, I provide an air chamber extending from end to end through the 75 holder which allows a free circulation of air and greatly assists in preventing the heat from permeating through the holder. This air chamber is indicated at 25, and it is formed between two strips of fabric used in the construction of the holder as will be 80 readily understood.

Many modifications and changes in details will occur to those skilled in the art without departing from the spirit and scope of my invention as defined in the claims; 85 therefore what I claim as new and useful and of my own invention and desire to secure by Letters Patent, is:—

1. In an iron holder, the combination with 90 a flexible body of heat insulating material, of independent metallic strip elements arranged on the bottom surface of said holder, all of said strips having a downturned end portion, coöperating with each other to form a pocket to receive therein the curved 95 portion of an iron handle, and two of said strips being provided with means for engaging the undersurface of the iron handle at said curved portion thereof.

2. In an iron holder, the combination with 100 a flexible body of heat insulating material, of independent metallic strip elements arranged on the bottom surface of said holder, all of said strips having a downturned end portion coöperating with each other to form 105 a pocket to receive therein the curved portion of an iron handle, and two of said strips being provided with means for engaging the undersurface of the iron handle at said curved portion thereof and at opposite 110 points along the shank of the handle of the iron.

3. In an iron holder, the combination with 115 a flexible body comprising a plurality of strips of cardboard arranged in layers upon each other, each layer being composed of separate strips with a space between the ends of said strips, and each strip overlapping the edge of the strip immediately beneath the same, a textile covering for said strips, 120 formed into pockets on opposite sides of the body of the holder, and means carried by the under surface of the holder for engaging the handle of an iron.

In testimony whereof I have hereunto set 125 my hand on this 30th day of November A. D., 1917.

WILLIAM HENRY HAWKES.
